UNITED STATES PATENT OFFICE.

J LOWE YOUNG, OF DETROIT, MICHIGAN.

BLOWPIPE AND BUNSEN BURNER.

No. 820,690.

Specification of Letters Patent.

Patented May 15, 1906.

Application filed November 15, 1904. Serial No. 232,862.

To all whom it may concern:

Be it known that I, J LOWE YOUNG, a citizen of the United States, residing at Detroit, in the county of Wayne and State of Michigan, have invented certain new and useful Improvements in Blowpipes and Bunsen Burners, of which the following is a specification, reference being had therein to the accompanying drawings.

10 The invention consists in the construction of a blowpipe and Bunsen burner, and particularly in the construction, arrangement, and combination of the various parts, as more fully hereinafter described, and particularly pointed out in the claims, whereby I 15 may attain in the same apparatus either the ordinary heating Bunsen flame or a blowpipe.

In the drawings, Figure 1 is a side elevation of my improved device, showing a small 20 crucible supported above the burner-nozzle as in position for use. Fig. 2 is a vertical central longitudinal section on Fig. 1 with the crucible omitted. Fig. 3 is a side elevation of the base. Fig. 4 is an enlarged section through the top of the blast-pipe for producing the blowpipe effect.

In the construction which I have herein shown A is a base, upon which is a central lug B.

30 C is a hinged standard bifurcated to embrace the lug B and pivoted on a pivot-pin D, passing through the lug and through the furcations. E is a set-screw for locking the standard at any desired angle to the base. 35 The top of the standard C is provided with the screw-threaded projection F, to which is secured a burner-tube G. This tube has upon it a shoulder a, and above the shoulder are the apertures b. Surrounding the tube 40 and resting on the shoulder a is the sleeve H, having complementary apertures c to the apertures b. The upper end of the tube G is preferably tapered, as shown, at I.

At the base of the tube G, I have provided 45 a gas-inlet nipple J, having a plug-valve K for controlling the admission of gas therethrough and constructed at its outer end to receive an ordinary rubber tube to supply the gas thereto from any suitable source. 50 This nipple has an extension L projecting within the tube G, and in the upper face of this extension is a port M of sufficient length to produce a vertical jet of gas within the tube when the valve K is opened. This gas- 55 jet is below the air-port b.

To use the device as a Bunsen burner, the

valve K being open, the sleeve H turned so that the ports b and c are in registration, the jet of gas discharged upward through the port M will draw air in through these ports 60 and commingle therewith to make the ordinary Bunsen flame, which will be discharged from the top. In this case the flame may be used to heat the crucible N, supported on the frame N' and connected to a sleeve O, which 65 fits about the upper tapered end of the tube G.

In the standard C is a nipple P, having a passageway therethrough which registers with a passage d in the standard. This passage d extends up through the upper end of 70 the standard, and in it is secured in any suitable manner a tube Q, which extends centrally of the tube G to at or near the upper end thereof. At its upper end I preferably provide it with the plug R, having a jet opening S therethrough. The nipple P is provided with a valve T for controlling the admission of air therethrough and is suitably shaped at its outer end to receive a supply- 75 pipe from any suitable source of air under 80 pressure.

When the device is to be used as a blowpipe, the valve K is opened, and also the valve T, and the sleeve H is turned so as to close the ports b in the tube G. The gas 85 entering in the tube G will be forcibly blown in a jet by the air under pressure issuing from the jet-opening S in the tube Q and mingling with the air will produce a blowpipe effect at the mouth of the tube G. This blowpipe 90 can be turned at any desired angle of the base and locked in its adjusted position by means of the set-screw E.

What I claim as my invention is—

1. The combination of a base, a tubular 95 burner-nozzle hinged to the base, valved air-inlets at the lower part of the nozzle, and a gas-supply nipple projecting laterally into the burner-nozzle, having an upwardly-directed jet-opening within the burner-nozzle, 100 and below said air-inlets.

2. The combination of a base, a tubular burner-nozzle hinged to the base, air-inlets at the lower part of said nozzle, a valved gas-supply nipple secured to and projecting into 105 the burner-nozzle and having an outlet below the air-inlets, and an apertured sleeve supported on the nozzle and acting as a valve for the air-ports.

3. The combination of a base, a standard 110 hinged thereto, a valved air-supply nipple secured to said standard, a burner-nozzle se-

cured to the standard, an air-blast tube secured centrally within the nozzle and communicating with the air-supply nipple, by a passage in said standard, laterally-projecting 5 air-inlets in the side of the burner and a gas-supply nipple for the burner-nozzle, arranged intermediate said air-inlets.

4. The combination of a base, a standard hinged thereto, an outwardly-extending nozzle mounted on the standard, an air-blast pipe extending centrally within the nozzle to a point adjacent its outer end, and having an inlet connection in said standard, a valved air-inlet in the nozzle adjacent its lower end, 10 and a gas-inlet arranged intermediate said air-inlets.

5. A combination blowpipe and Bunsen

burner, comprising a base, a standard hinged thereto, a valved air-supply nipple secured to said standard, a burner-nozzle secured to 20 the standard, an air-tube secured centrally within the nozzle and communicating with the air-supply nipple, valved air-inlets for the nozzle, a gas-supply nipple in the burner-nozzle between the air-supply nipple and the 25 valved air-inlets, and a detachable crucible-support connected to said burner at its upper end.

In testimony whereof I affix my signature in presence of two witnesses.

J LOWE YOUNG.
